UNITED STATES PATENT OFFICE.

JAMES C. MCGUIRE, OF BRIDGEWATER, MASSACHUSETTS.

BLOCK-HOLDING ATTACHMENT FOR LEATHER-CUTTING MACHINES.

1,218,433.

Specification of Letters Patent.

Patented Mar. 6, 1917.

Application filed May 27, 1916. Serial No. 100,275.

To all whom it may concern:

Be it known that I, JAMES C. MCGUIRE, a citizen of the United States, residing at Bridgewater, in the county of Plymouth 5 and State of Massachusetts, have invented certain new and useful Improvements in Block-Holding Attachments for Leather-Cutting Machines; and I do hereby declare the following to be a full, clear, and exact 10 description of the invention, such as will enable others skilled in the art to which it appertains to make and use the same.

This invention relates to an attachment for sole, or leather cutting machines, and 15 the primary object of the invention is to provide a substantially U-shaped bar having depending wedge shaped lugs formed upon the ends of its legs for insertion in recesses formed in the bed plate of a sole or 20 leather cutting machine for holding the die blocks against accidental longitudinal or lateral movement, thereby eliminating the necessity of tying the die blocks to the bed plate or frame of the cutting machine by 25 ropes, or other similar material for preventing the longitudinal sliding or slipping movement of the die blocks and their interference with the working parts of the machine. 30 With the foregoing and other objects in view this invention consists in such novel features of construction, combination and arrangement of parts as will be hereinafter more fully described, illustrated in the accompanying drawing and claimed.

In describing the invention in detail reference will be had to the accompanying drawing wherein like characters designate like and corresponding parts throughout 40 the several views, and in which:—

Figure 1 is a side elevation of a beam cutter for leather or other analogous material, showing the invention applied thereto.

Fig. 2 is a fragmentary perspective of the bed plate of the cutter showing the invention applied thereto.

Fig. 3 is a detail perspective of the block holding attachment, and

Fig. 4 is a section on the line 4—4 of Fig. 3.

Referring more particularly to the drawing, 1 designates a beam cutting machine, for leather or analogous materials, of ordinary construction which includes a bed plate 2 and a die block 3 of ordinary con-

struction, which die block rests upon the upper surface of the bed plate 2. In the operation of the cutting machine, the vibration causes the die block 3 to slip or move longitudinally along the upper surface of the bed plate 2, and to prevent this movement which often interferes with the operation of the machine, the improved holding clamp illustrated in Fig. 3 and indicated by the numeral 5 is provided.

The block holding clamp 5 is constructed of metal or analogous material and comprises a substantially U-shaped body portion having a bight portion 6 and legs 7 and 8. 70 The legs 7 and 8 have depending wedge shaped lugs 9 formed upon their outer free ends and depending from their under surfaces. The outer side of the free ends of the legs overhang the outer surfaces of the wedge shaped blocks 9. The wedge shaped blocks 9 are provided for seating the sockets 10 which are formed in the bed plate 2 of the cutter and ordinarily receive the usual form of wedges employed for holding the 80 die blocks in place. The legs 7 and 8 of the block holder 5 extend along the upper surface of the bed plate and the bight portion 6 extends transversely across the upper surface of the bed plate at one end of the same. 85 The inner surfaces of the legs 7 and 8 and of the bight portion 6 engage the lower portion of the die block, and hold this die block against accidental longitudinal or lateral movement upon the surface of the bed 90 plate, thereby eliminating the liability of its slipping out of place during the operation of the machine and interfering with the working parts of the same.

In applying the improved block holding 95 attachment to the leather cutting machine, one of the attachments are mounted upon the upper surface of each end of the bed plate 2 for engagement with each end of the die block 3 as indicated in Fig. 1 of the 100 drawing.

In reducing the invention to practice, certain minor features of construction, combination and arrangement of parts may necessitate alterations to which the patentee 105 is entitled provided such alterations are comprehended within the scope of what is claimed.

What is claimed is:—

1. The combination with an ordinary 110 leather cutting machine including a bed plate and a die block removably mounted

- upon said bed plate, of a substantially U-shaped bar mounted upon the upper surface of said bed plate and having the inner surfaces of its legs and bight portion engaging portions of the sides and end of said die block, and means for connecting said bar to said bed plate for preventing accidental movement of the die block upon the said plate.
- 10 2. The combination with an ordinary leather cutting machine including a bed plate having sockets formed therein and a die block removably mounted upon said bed plate, of a substantially U-shaped member mounted upon the upper surface of said bed plate and having the inner surfaces of

its legs engaging portions of the sides of said die block and the inner surfaces of the bight portion engaging a portion of the end of said die block, and wedge shaped blocks 20 formed upon and depending from the under surfaces of the free ends of the legs of said member and seating in said sockets for preventing accidental movement of said member.

25

In testimony whereof I affix my signature in presence of two witnesses.

JAMES C. McGUIRE.
